WELL PUMP

John B. Davis, Dallas, Tex.

Application June 10, 1939, Serial No. 278,537

9 Claims. (Cl. 166—1)

This invention relates to new and useful improvements in pumping units.

This application is a continuation in part of the co-pending application, Serial No. 272,488.

One object of this invention is to provide a unit similar to that described in the aforementioned co-pending application but without the use of a central balanced hydraulic unit.

Another object of the invention is to provide means for agitating a well when said well has ceased to flow under its own pressure.

Another object of the invention is to provide agitating means for a well which means comprises an elementary unit of a permanent well pumping system.

A further object of the invention is to provide means for counterbalancing the rod load of a pumping unit, said means being operated by the gas pressure within a well casing.

Another object of the invention is to provide means for utilizing gas head pressure within a well casing as a pressure medium for operating a rod load counterbalancing means.

Still another object of the invention is to provide means for converting the wet gas within a well to a dry gas for use within a counterbalancing unit thereby decreasing the danger of using a highly inflammable explosive wet gas.

A still further object of the invention is to provide means for regulating the pressure prior to the entrance of said pressure into a counterbalancing unit from a well.

Another object of the invention is to provide a mechanically operated and controlled valve for later use in connection with a central power plant.

Another object of the invention is to provide an automatic trip valve which valve controls both the pressure inlet port and the pressure exhaust port.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is an elevation of an oil well having a counterbalancing means attached thereto and constructed in accordance with the present invention.

Figure 2 is a view similar to Figure 1 having a unit, pressure operated without an assisting motor.

Figure 3 is a view of still another form of well pumping means.

Figure 4 is an elevation of the automatic trip valve.

Figure 5 is a transverse, vertical, sectional view 5 of the valve shown in Figure 4.

Figure 6 is a view partly in elevation and partly in section of the mechanical control valve used in cooperation with a central plant.

Figure 7 is a transverse, vertical, sectional view 10 of the release valve employed on the mechanical control valve, and

Figure 8 is an enlarged detail view of the valve control mechanism.

As is known in the art, ordinarily when a well 15 is first "brought in", sufficient gases are formed to such a great extent of pressure that in their escape, the gases will carry fluid upwardly therewith, thereby producing a flowing well. However, the gas pressure within some of these wells is 20 sufficient to operate a well for only a short period of time. Also other wells may flow naturally for longer periods. In time, as the oil level is lowered so also is the gas pressure decreased until such time that, although gas is still escaping under 25 comparatively high pressure, the velocity of the gas is insufficient to raise the fluid to the top of the well from its lowered level.

When the well ceases to flow under its own pressure it is then necessary for the operator to 30 employ what is known as an agitating means or, at this early stage of operation, install a complete and highly expensive well pumping unit. To date the agitators now procurable on the open market have proven themselves to be very unsatisfactory to the average operator, not only because of the initial cost of an agitating unit, but also that at such time as the gas pressure decreases to too great an extent the operator is forced to discard his agitating unit and go to the 35 further expense of installing a regular pumping unit.

The foremost object of this invention is to provide a unit which may be operated from the gas 45 head pressure within the well casing as an agitating means as long as sufficient pressure remains within the well casing. When the pressure fails, it is only necessary for the user of this invention to employ means for introducing pressure into the primary unit that had been used as an agitating medium. Thus it will be seen that in using a device of this type a well operator need only buy a portion of a complete pumping unit to be used as an agitator and later buy the

remainder of the unit to be used as a regular sucker rod pump.

In the drawings, the numeral 10 designates a well casing having the usual casing head 11 thereon. Well tubing 12 extends through the casing while the usual reciprocating sucker rods 13 are centrally disposed within the tubing. The upper end of the sucker rod is connected to a "walking beam" 14 by a swivel joint 15.

10 The walking beam 14 is pivoted at 16 on the upper end of a suitable standard 17, while a connecting link 18 is pivoted at 19 to said beam and connected at its other end to an actuating arm 19 of a gearing unit 20, which is mounted on a 15 suitable base 21.

15 Adjacent the connection 15 is a pivotal connection 21 to which is fastened the upper end of a piston 22, which is confined within a cylinder 23 as a counterbalancing medium. The 20 piston is actuated vertically by means of the gas head pressure within the well casing 10. The pressure is introduced into the cylinder 23 by means of a connecting pipe 24 in which is mounted an automatic trip valve 25 which valve is actuated by a link 26 connected at one end to the valve, while stop lugs 26' are positioned on said link, which link is slidably engaged by slotted plate 14' secured to the underside of the beam 14. Thus, the valve 25 is actuated when the plate 30 strikes either the upper or lower lug whereby a quick valve action is had at such time as the beam reaches either of its extreme positions.

25 A cut-off valve 27 is mounted in the line 24 adjacent the well casing, while a constant pressure 30 reducer 28 is also connected in the line. 35

By observing Figures 4 and 5 the details of the 40 automatic trip valve may clearly be seen. An actuating arm 29 is connected at its outer end to the link 26 and at its inner end to actuating lug arms 30 which arms are rotatably mounted on a 45 shaft 31. The shaft extends into a valve housing 32 which is substantially circular in cross section. An operating arm 33 is keyed to the shaft 31 in such a manner as to rotate said shaft when said arm is moved. A weight 33' is positioned on the extreme outer end of the shaft, whereby when the lug arms 30 are moved due to their connection to the link 26 by means of the arm 29, said operating arm will be overbalanced by the weight after the center of gravity of said 50 arm 33 is reached, thus causing a quick valve action.

55 A semi-circular valve 34 is mounted within the housing 32 and connected to the shaft by arms 35, said valve member being fixedly mounted on said shaft 31. An opening 36 is provided in the member 34 intermediate the ends thereof whereby if the inlet port A is open the outlet port B will be closed, while the cylinder port C will at 60 all times remain open.

65 Thus movement of the arm 26 will rotate the shaft due to the members 29, 30 and 33. Rotation of the shaft will change the position of the opening 36 to open or close either of the ports A and B. From the foregoing it may be seen that when the opening 36 is in the position shown in Figure 5, the header gas may enter the cylinder 70 23 through the valve 25 by way of the ports A and C. Gas is introduced in this manner on the upstroke of the sucker rods 13. The link 26, being connected to the beam 14, will be actuated on the upstroke of said beam. The following operation of the valve has been hereinbefore explained, that the arm 33 will rotate the shaft 31 to change 75 the position of the opening 36, which change will

close the inlet port A, and open the exhaust port B, whereby the gas pressure within the cylinder 23 may escape back through port C and out into exhaust port B. It is to be noted that an upright pipe B' is provided whereby the escaping gases 5 may be burned, or otherwise disposed of. A cut-off valve 25' is mounted in the pipe B' whereby the exhaust may be controlled to determine the speed of the downstroke of the piston 22. It is to be noted that this valve 25' is not used when 10 a gear box is employed.

In operation, for example, a gas head pressure of 500 pounds is in a well and only 150 pounds is needed to perform the counterbalancing operation of the piston and cylinder 22 and 15 23, respectively, the constant pressure reducer 28 would be set at its secondary end at 150 pounds, thereby allowing for constant pressure upon the piston 22. This pressure is so regulated as to in no way interfere or injure the 20 gearing unit 20.

Thus, if desired, sufficient pressure may be introduced into the cylinder 23 to overcome both the "rod load" and the "fluid load", whereby only the weight of the rods on the downstroke thereof will be imposed upon the gearing unit 20, to lengthen the operation period of said gearing unit indefinitely.

From the foregoing it may be seen that with a unit as hereinbefore described, an agitating medium is obtained, said medium requiring only the cost of the gearing unit up-keep.

In Figure 2, is shown a unit which does not employ a gearing unit. This type agitator is for use on a well having a higher gas head pressure which enables an operator to raise both the rod and fluid loads by means of the gas head pressure.

The only difference between the agitator shown in Figure 2 and that form hereinbefore described is that a cable connection 40 between the sucker rods 13 and the beam 14 is employed. An arcuate member 41 is substituted for the pivotal connection 15 whereby a direct vertical pull is had on the sucker rods. Also the gearing unit 20 and its accompanying parts are eliminated. Also the exhaust control valve 25' is employed with this type agitator. Otherwise all parts of this unit are identical to the hereinbefore described form and bear similar reference numerals, thereby eliminating the necessity of repetition of the description of said identical parts.

In Figure 3, another form of agitator is shown. In this form the well casing, casing head, tubing, cylinder, piston, trip valve, cut-off and connecting pipe are identical to that of the forms shown in Figures 1 and 2 and bear like reference numerals. However, the walking beam 14 and standard 17 are substituted by a wheel 45 rotatably mounted on uprights 46 secured to the upper end of 60 the piston 22. A cable 47 is positioned over a wheel 45 and secured at one end as at 48 to the sucker rods 13, while the other end is fixedly secured at 49 to the cylinder mounting. The piston 22, as has been explained, is controlled 65 by the trip valve 25, hereinbefore described in detail.

The operation of this mechanism may clearly be seen by observing Figure 3. As the piston and its cooperating wheel 45 travel upwardly, so the 70 sucker rods will likewise move upwardly due to the cable connection 47. It is to be noted that a condenser gas separator 50 of any conventional type, is disposed within the line 24. The purpose of this condenser is to convert "wet" gas

into "dry" gas thereby greatly reducing possible frictional explosions. This condenser may be employed on any of the herein described units, as a safty feature.

From the foregoing it may be seen that as long as a gas head pressure remains in a well, the above described units may be employed as agitators. If one operator has for instance, twenty wells, two of which are "gassers", while the 10 remaining wells contain only a small amount of gas, the "gasser" well may easily be connected to the wells containing only a small amount of gas whereby these wells may be operated off the "gasser" wells as has been explained.

After an indefinite period, the gas head pressure will be reduced to such an extent as to make the above described operations impossible. At this time the operator may only add the "central plant" system, (shown, described and claimed in 20 applicant's copending application, Serial No. 272,488) to complete a highly efficient counterbalanced pumping unit. It is to be particularly noted that an operator need not discard any equipment, as the unit hereinafter claimed comprises a primary portion of applicant's above 25 identified copending application.

In Figures 6, 7 and 8, is shown a mechanical power control valve 50 which may be substituted for the electrical valve claimed in the hereinbefore mentioned copending application.

As the control valve 50 is shown, described and claimed in the aforesaid application claim is made only to the valve actuating mechanism.

The valve 50 comprises a housing 51 having a piston 52 slidably mounted therein which piston has an upwardly extending piston rod 53 having a gear rack 54' formed on one side thereof. A sprocket wheel 54 is rotatably mounted on a shaft 55', while a chain 55 is arranged 40 over said wheel, said chain engaging the spokes of said sprocket wheel. A weight 56 is secured to one end of the chain while a tape 56' is secured to the other end of said chain. An idler pulley 57 is so arranged as to accomplish a direct vertical movement of the chain until said chain engages the wheel.

A weighted arm 70 is fixedly secured on the sprocket wheel shaft 55' while lugs 71 are adjustable in arcuate slots 72 formed in the wheel 54. The lugs 71 are arranged to strike the weighted arm to produce an action similar to that of the valve 25. As the lugs move the arm, the shaft is turned to actuate the gear rack through the medium of a pinion gear 73 engaging said rack 54 thereby actuating the valve 50.

The other end of the tape is suitably secured to the piston 22 whereby movement is imparted to said tape to accomplish rotation of the sprocket wheel in cooperation with the weight 56. It is to be noted that said tape is confined within a conduit 59 between said chain and said piston 22.

Vent valves 60 are provided at the upper and lower ends of the housing 51. The valve comprises a housing 61 being closed at one end by a ball valve 62 and a needle valve 63 at its other end. A communicating port 64 is provided between the members 62 and 63 which port communicates with the interior of the housing 51. The purpose of this valve is to eliminate any possibility of vacuum or compression which may interfere with the operation of the valve 50. It is to be noted that adjustment of the needle valve 63 will regulate the speed of the piston 52 as well as preventing said piston from "banging"

against the valve housing at the termination of the strokes of said piston.

From the foregoing it may be seen that a highly efficient and economical agitating unit may be had, which may later be converted into 5 a counterbalanced pumping unit. As has been stated, a user of the above described agitating means need not discard any of his original equipment but only add thereto. Also well gases are utilized before being burned or otherwise disposed of. It is to be noted that the hereinbefore described invention is used with great efficiency on unusually deep wells which have heavy rod and fluid loads, as this unit may be arranged, as has been stated, to raise both the maximum and 10 rod and fluid loads.

Manifestly, the construction as shown and described is capable of some modification and such modification as may be construed within the scope and meaning of the appended claims is 20 also considered to be within the spirit and intent of the invention.

What is claimed is:

1. A well agitating unit comprising a pivoted walking beam, actuating means connected to one 25 end of said beam, sucker rods connected to the other end of said beam, balancing means connected to said walking beam intermediate said sucker rod connection and said pivot point of said beam, and means for utilizing the gas pressure within said well as an operating medium of said balancing means.

2. An agitating unit for a well comprising reciprocable agitating means within said well, means for actuating said reciprocable agitating 35 means, and means for utilizing the gas head pressure within said well as a counterbalancing means for relieving the rod and fluid loads from said agitating actuating means.

3. An agitating unit for a well comprising 40 agitating means within said well, actuating means for operating said actuating means, counterbalancing means connected to said actuating means, a line conducting the gas head pressure from said well to said counterbalancing means, and a pressure reducer mounted in said line to maintain a predetermined pressure upon said counterbalancing means.

4. A plurality of balanced agitating units comprising agitating means, means for pressure operating said agitator means, a "gasser" well for supplying gas head pressure to said agitator operating means to all of said agitating units, means for converting said well gases from "wet" gases to "dry" gases, and means for regulating the 50 pressure applied to said agitator operating means.

5. A well agitating unit comprising agitating means within said well, pressure operated means for reciprocating said agitating means, means for introducing gas head pressure from said well to 60 said agitator reciprocating means, means for regulating said introduced gas head pressure, means for converting said well gases from wet gases to dry gases, and valve means in said introducing means for regulating the input pressure and exhaust pressure to and from said agitator reciprocating means.

6. A well agitating unit as set forth in claim 5, said valve means being actuated by said agitator reciprocating means and including a pressure 70 port, a cylinder port, an exhaust port, control means to close said exhaust port and open said pressure port, means for changing the position of said control means to open said exhaust port and close said pressure to escape rearwardly from

said cylinder port and upwardly through said exhaust port, and means connected to said exhaust port for disposing of said well gases as the same are exhausted after use.

- 5 7. A mechanically operated control valve to be used with a counterbalanced pumping unit including a housing, a reciprocable piston in said housing, control ports in said piston, a piston rod having a gear rack formed thereon, a shaft having a pinion gear keyed thereon, said gear rack and said pinion arranged in constant mesh, a sprocket wheel rotatably mounted on said shaft, means connected to said sprocket wheel and said well pumping unit to rotate said sprocket wheel, 10 15 a weighted lever keyed on said shaft adjacent said sprocket wheel, adjustable actuating lugs on said wheel whereby when said wheel is rotated said weighted lever is actuated to rotate said shaft to change the position of said piston through the medium of said gear rack and pinion. 20 8. A well agitating unit comprising agitating means within said well, pressure operated means

for reciprocating said agitating means, means for introducing gas head pressure from said well into said agitator reciprocating means, means for controlling gas head pressure input into said reciprocating means, a trip valve for controlling said pressure input and exhaust, and means for regulating the velocity of the exhaust from said reciprocating means. 5

9. An agitating unit for a well comprising reciprocable agitating means within said well, a cylinder, a piston within said cylinder, said piston connected to and actuating said reciprocable agitating means, an introduction means for conducting gas head pressure from said well to said cylinder to actuate said piston and reciprocable 10 15 agitating means, valve means for controlling gas head pressure input and exhaust from said cylinder mounted in said line, and valve means connected in the exhaust port of said valve for determining the speed of descension of said piston. 15

JOHN B. DAVIS.
